(57) **CLAIM**

The ornamental design for a temple for eyeglasses, as shown and described.

DESCRIPTION

FIG. 1 is a front view of a temple for eyeglasses of the present invention;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a top perspective view thereof;

FIG. 8 is a bottom perspective view thereof;

FIG. 9 is an enlarged sectional view taken along line 9-9 of FIG. 3 and terminating at line 901-901;

FIG. 10 is an enlarged sectional view taken along line 10-10 of FIG. 3 and terminating at line 1001-1001;

FIG. 11 is an enlarged sectional view taken along line 11-11 of FIG. 2 and terminating at lines 1101-1101; and,

FIG. 12 is a perspective view showing the temple for eyeglasses in a state of use.

The broken lines in FIGS. 1-11 show portions of the article that form no part of the claimed design. The additional broken lines in FIG. 12 show portions of the environment that form no part of the claimed design. The alternate long and short dash lines show boundaries of the claimed design and form no part thereof.

The alternate long and short dash lines are merely the boundary lines between the claimed parts and the non-claimed parts.
